DESIGN FOR A STAMP PAD BOX

Laurence W. Kendrick, Wellesley, Mass., assignor to The Carter's Ink Company, Cambridge,
Mass., a corporation of Massachusetts

Application December 19, 1940, Serial No. 97,449

Term of patent 14 years

To all whom it may concern:

Be it known that I, Laurence W. Kendrick, a citizen of the United States and resident of Wellesley, in the county of Norfolk, State of Massachusetts, have invented a new, original, and ornamental Design for a Stamp Pad Box, of which the following is a specification, reference being had to the accompanying drawing, forming part thereof.

Fig. 1 is a top plan view of a stamp pad box, showing my new design.

Fig. 2 is a front elevational view thereof; and Fig. 3 is a side elevational view thereof.

I claim:

The ornamental design for a stamp pad box, as shown.

LAURENCE W. KENDRICK.
